UNITED STATES PATENT OFFICE.

GEORGE MICHAEL MYERS, JR., OF CHARLESTON, SOUTH CAROLINA.

THREAD AND IMPLEMENT HOLDER.

1,401,811.

Specification of Letters Patent. Patented Dec. 27, 1921.

Application filed December 16, 1919, Serial No. 345,291. Renewed July 15, 1921. Serial No. 485,037.

To all whom it may concern:

Be it known that I, GEORGE M. MYERS, Jr., a citizen of the United States, and a resident of the city of Charleston, in the county of 5 Charleston and State of South Carolina, have invented a new and Improved Thread and Implement Holder, of which the following is a full, clear, and exact description.

This invention relates to the art of 10 crocheting or knitting, and more particularly to a box for holding the crochet thread.

An object of the invention is to provide 15 a container for holding balls of crochet thread, or spools of crochet thread, which will feed the thread out as used to prevent it from becoming tangled or knotted during crocheting, knitting, or sewing operations.

20 At times great inconvenience occurs to ladies and others crocheting and doing needle work because of the thread becoming knotted, and, further, because the crochet ball may fall from the operator's lap on the 25 floor and become dirty or entangled with other sewing work, thus causing considerable inconvenience in the carrying out of this work.

It is fitting, therefore, that an object of 30 my invention is to provide a crochet-ball or other containing box which will obviate such disadvantages and inconveniences, and, further, which will provide adequate means for holding one or more balls of crochet thread 35 or spools of thread to keep the thread clean, smooth and straight, free from tangles and ready at all times for crocheting, knitting and sewing work.

It is a further purpose of this invention 40 to provide a simplified form of attachment means for fastening the device to one's clothing, so that the thread is always available and close to the work done.

Likewise, a purpose of my invention, and 45 one of the important features thereof, resides in the provision of a needle-holding means for securing a needle to the box to prevent its loss when not in use.

With the above principal objects and 50 others in view, the invention has relation to a thread container and crochet-needle holder as set forth in the appended claims, described in the following specification, and illustrated in the accompanying drawings, 55 wherein:

Figure 1 illustrates an elevation of the

thread container attached to the operator's clothing, there being a portion of the container broken away to disclose the thread.

Fig. 2 illustrates a sectional view taken 60 on the line 2-2 of Fig. 1.

Fig. 3 illustrates a fragmentary sectional view taken on the line 3-3 of Fig. 1.

A thread-holding box constructed in accordance with my plan and conception embodies a container 4 constructed of any suitable material, such as celluloid or fiber, and formed in any appropriate shape. It is practical to build the container 4 in cylindrical form with one end closed and the 70 other end open. There is provided a cover cap 5 which slips over the open end of the container 4, and the cover cap has hooks 6 which engage pins 7 fixed to the container 4. By subjecting the cover cap 5 to slight rotation the hooks 6 will disengage the pin 7 and the cover may be removed for withdrawing the ball of thread or for reinserting another ball of thread. The container 4 is provided with an opening 8 of 80 any appropriate form, there being an elongated slot shown in the drawings. The ball of thread 9 carried in the container 4 is unwound to expose one end of its thread 10 for use, and the thread may be withdrawn from 85 the box at intervals for carrying on the needle work.

A number of fastener eyes 14 are secured to the thread container 4, and the fastener eyes provide securing means for attaching 90 a carrier bail 15. The lower ends of the carrier bail are passed through the fastener eyes and then bent to form loops or eyes 16 and the free ends bent to form with the members of the bail clamps 17. The upper 95 portion of the bail 15 is shaped to form a clasp 18. The clasp 18 is constructed by bending the bail 15 back on itself until the two clasp members 18 range and bind one parallel on the other.

The carrier bail 15 is constructed of appropriate spring material which provides flexibility in the clasp 18 and also in the two clamps 16 and 17. The device is hooked on to the operator's clothing by pinching 105 the clothing and thrusting the clasp 18 of the carrier bail down on the clothing to grasp the cloth between the two clasp parts 18, as shown in Fig. 1.

The crochet needle 20 is inserted in the 110 clamps 16 and 17 by pushing the small end of the needle forward through the loop

clamp 16 and jamming the shank of the needle down in the open clamp 17. In this way the needle is securely held to the carrier bail with the result that it does not become loose and is always available for use.

The use of this thread carrier or crochet fixture will always insure the availability of the crocheting materials by keeping the needle and the thread in order. The carrier 10 may be quickly clasped to one's dress or removed therefrom without damage to the dress. When crocheting with the use of this fixture, the crocheting operation may be temporarily stopped at any time for performing 15 other duties and the device left suspended on one's clothing, and there is no inconvenience experienced in wearing the crochet box for it is compact, small, light in weight, and an article of extended value and household usefulness.

Having thus described my invention what I desire to secure by Letters Patent is:

1. An appliance of the character specified, comprising a thread container provided in a 25 side with a thread opening, a cover removably fitted to one end of the container, and a suspending bail attached to the container and provided with a centrally disposed suspending clasp and terminal eyes and clamps, 30 the eyes serving as the connecting means be-

tween the bail and container and the clamps as holding means for a crochet needle.

2. An appliance of the character specified, comprising a thread container and a suspending bail therefor provided with terminal eyes and clamps serving as connecting means between the bail and container, and as holding means for a crochet needle. 35

3. An appliance of the character specified, comprising a thread container and a suspending bail therefor having its terminal portions bent to provide container connecting elements and crochet needle holding means. 40

4. An appliance of the character specified, comprising a thread container, and a suspending bail therefor having its middle portion of loop form and its terminal portions consisting of attaching eyes and needle holding clamps. 45

5. An appliance of the character specified, comprising a thread container provided in a side with a thread slot, a cover, detachable securing means between the cover and the container, a bail having a centrally disposed 55 clasp and terminal eyes and needle holding clamps, and eyes on a side of the container engaging the eyes of the bail.

GEORGE MICHAEL MYERS, JR.
